Primary Examiner — Marianne Pandozzi(74) *Attorney, Agent, or Firm* — John W. LaBatt; Hoffman Warnick LLC(57) **CLAIM**

The ornamental design for a water treatment device, as shown and described.

DESCRIPTION

FIG. 1 is a perspective view of a water treatment device showing our new design;

FIG. 2 is a top plan view thereof;

FIG. 3 is a bottom plan view thereof;

FIG. 4 is a front view thereof; and,

FIG. 5 is a right side view thereof.

The broken line showings are for illustrative purposes only and form no part of the claimed design.
